UNITED STATES PATENT OFFICE

2,088,871

MAINTENANCE TRAVELER FOR BRIDGE SPANS

William H. Ringe, Berkeley, Calif.

Application January 30, 1937, Serial No. 123,209

15 Claims. (Cl. 304—9)

This invention relates to bridge span and maintenance travelers for use on large bridges, and of the type disclosed in my United States Patent No. 2,067,344, issued January 12, 1937, and has for its principal objects improvements in such structures whereby lower cost and weights are achieved, and other advantages are effected as will appear in the following description and accompanying drawings.

5 In the drawings:

10 Figure 1 and Figure 1a form together a side elevation of my improved traveler applied to a diagrammatic cross section of the Golden Gate Bridge span, the figures being arranged to overlap slightly at the center as indicated by the similarly numbered parts;

15 Figure 2 is a cross section of the traveler as seen from the line 22 of Figure 1, and showing the end elevation of the extension frame or hanging cross traveler towers thereof.

20 Before describing the drawings in detail it may be stated that in my issued patent above mentioned, my maintenance traveler comprised a latticed beam extending crosswise below a bridge and suspended on rollers from tracks secured to the bridge so that the beam could be rolled along the bridge the length of its span, and the fact that the beam preferably extended beyond both sides of the bridge so as to make the outsides thereof also accessible to workmen on the traveler, made it necessary to, in that form of the invention, suspend it low enough to clear the main side girders or trusses of the bridge which, on the Golden Gate Bridge, extend about sixteen feet below the main cross beams of the bridge. Therefore in order to make the under parts of the bridge accessible a traveling work tower was provided on the traveler.

25 The present improvement is based principally on shortening the traveler beam about thirty feet and suspending this shorter cross beam or traveler relatively close to the under sides of the main cross beams of the bridge, and providing a traveler on the traveler beam with downwardly extending portions which may be termed "hanging work towers". These latter towers may be rolled along the traveler to adjacent either inner side of the main bridge side trusses, and the lower ends of the suspended "tower" frames being extended outwardly forming working platforms from which the exteriors of the main bridge trusses are accessible. This construction greatly reduces the cost and weight of the traveling structure which for the Golden Gate Bridge 30 would run from about 7 to 10 tons, depending

upon whether steel or aluminum alloy metal construction were used.

35 In the drawings, the Golden Gate Bridge has merely been used to show the application of my improved maintenance traveler, and the cross section of the bridge, on account of its great mass of open work of trusses, girders, beams, braces, etc. is herein diagrammatically represented. The side trusses which are spaced some eighty-eight feet apart outside to outside, are designated 1, the main cross beams or girders 2, angular braces 3, and deck structure including its floor beams and road pavement 4.

40 Beneath the main bridge beams and running crosswise of the bridge is my traveler beam 5. This traveler beam is preferably of latticed construction on account of its great size, and it is rollably suspended adjacent the under side of the main bridge beams 2 by rollers 6, rolling on tracks 7 suitably suspended from or secured to the bridge structure. I prefer to use a somewhat flexible suspension of these rails as indicated at 8, so that the rollers, which engage opposite sides of both rails, will not bind due to contraction, expansion, or warping of the bridge structure or the traveler structure. Two suspension rails are indicated, though any number may be used, and at least one set on both rails is driven preferably by power to propel the beam along the span of the bridge. The propelling wheels on the two tracks must be mechanically or electrically connected so as to work in synchronism, and in the drawings I show either A. C. synchronous motors 9, or compound wound D. C. motors, at both sets of rollers operated from a current generated on the traveler itself as by an internal combustion engine driven electric generator set indicated at 10 in the drawings. Suitable wiring and controls, not shown, are of course provided.

45 The generation of the operating current on the traveler is of considerable importance as it avoids the danger of electrolysis in a bridge structure, and also the difficulty of getting good trolley or rail contact in an atmosphere of damp salt air, such as almost constantly prevails at the Golden Gate Bridge over the entrance to San Francisco Bay.

50 The traveler beam is of a length to just come within the angular bridge truss braces 3 which extend about ten feet inside of the inner faces of the bridge side trusses 1, and a rolling extension frame 11 is provided which is rollably suspended by rollers 12 rolling on tracks 13 on opposite sides of the traveler beam as best shown in Figure 2. Frame 11 may be rolled along the

traveler beam to any point and to extend beyond either end thereof to come close to the inner sides of the bridge side trusses 1 as indicated at X in Figure 1.

5 Rollable extension frame 11 is a skeleton metal structure and may be either power or hand propelled by any suitable means not shown, and at opposite ends of the frame are depending extensions or what may be termed hanging work "towers" 14 (taking the place of the standing work towers shown in my issued patent aforesaid). These towers 14 are provided at their lower ends with outwardly extending portions 15 which, when the frame 11 is rolled over to one end of the traveler beam, extend under and beyond the bridge side truss 1 at that side of the bridge as shown at XX in Figure 1, to thereby afford access to the outer side of the trusses for painting or repairs, ladders being used on the extensions, 20 if desired.

The frame 11, or cross traveler as it may be termed, is provided with several work platforms 16, 17, 18 and 19 spaced about 6' 6" above one another, so that a workman standing on one 25 can reach all parts of the adjacent bridge structure from one platform or floor to the next, and the several platforms are made accessible to the workmen by suitable stairways or ladders 20, 21. The platforms or floors are preferably about a dozen feet wide for an installation of this kind 30 for a bridge the size of the Golden Gate Bridge, and the upper platform or floor 16 makes the under sides of the main bridge beams 2 accessible, and ladders may be used upon it to reach other parts between the big beams, or additional lift platforms may be added for reaching up between the bridge girders 2 as shown in my issued 35 patent before mentioned.

It should also be noted that while I show a 40 cross traveler frame 11 with a depending tower 14 at each end which requires rolling from one end of the traveler beam 5 to the other to bring the towers respectively adjacent the inner sides of the bridge side trusses 1, it is evident without 45 further drawings that two shorter cross travelers may be used, each with but one depending tower on its outer end to reach the adjacent bridge side truss if desired, and my appended claims are intended to cover any such modification.

50 The traveler beam is constructed of two spaced, preferably latticed, side beams 5 joined by several smaller latticed beams 5', and the rollers 12 of the cross traveler or extension frame 11 are deeply flanged to engage over the tracks 13 so that 55 any spreading of the side members 5 is impossible.

Both outer sides of the cross traveler are enclosed in wire netting 22, also the angular walls as at 23 in Figure 2 which corresponds to a plane 60 at right angles to the plane of the drawings at the under sides of the ladders or steps 20 of Figure 1, at the line designated 23, and also the sides and outer ends of the extensions 15 are similarly wire enclosed, so that a workman cannot fall off by accident and the only open place is upward and at the ends of the vertical sides 14 of the cross traveler.

Also to be noted is that since the main side 70 trusses 1 of the bridge are of open lattice or girder work, it is manifest that their outer sides may also be reached by the use of heavy planks extended from any floor through the side trusses, the planks being properly secured to the floor or platform and preferably provided with guard 75 rails.

As the details of bracing and other structural construction are well understood and not involved in the invention, no further description is thought necessary.

Having thus described my improved bridge 5 maintenance traveler, it will be seen to be adapted to any type of large span bridge where maintenance and frequent inspection are important.

I claim:

1. Bridge span inspection and maintenance apparatus comprising a traveler frame extending transversely of and under the bridge span, means rollably suspending the traveler frame for rolling longitudinally of the bridge, an extension frame carried by the traveler frame arranged to be extended beyond the end of the traveler frame and arranged to support workmen in accessible relation to the bridge, and means affording accessibility of workmen from said extension frame to the traveler frame. 10 15 20

2. Bridge span inspection and maintenance apparatus comprising a traveler frame extending transversely of and under the bridge span, means rollably suspending the traveler frame for rolling longitudinally of the bridge, an extension frame carried by the traveler frame arranged to roll therealong and extend beyond either end of 25 said traveler frame to a point adjacent the sides of the bridge, a platform for workmen on said extension frame, and means affording accessibility of workmen from said platform to said traveling frame. 30

3. Bridge span inspection apparatus comprising a traveler frame extending transversely of and under the bridge span, tracks carried by the 35 bridge extending longitudinally thereof, and rollers carried by the traveler engaging the tracks adapting the traveler to roll along the bridge span, means for driving said rollers to propel the traveler, and means flexibly supporting the 40 tracks relatively to prevent binding of the rollers through contraction, expansion or warping of the bridge and traveler. 45

4. Bridge span inspection apparatus comprising a traveler frame extending transversely of 45 and under the bridge span, tracks carried by the bridge extending longitudinally thereof, and rollers carried by the traveler engaging the tracks adapting the traveler to roll along the bridge span, means for driving said rollers to propel the 50 traveler, including an engine-dynamo electric generating plant carried by the traveler, and electric motor operatively connected to the roller. 55

5. Bridge span inspection apparatus comprising a traveler frame extending transversely of 55 and under the bridge span, tracks carried by the bridge extending longitudinally thereof and rollers carried by the traveler engaging the tracks for rolling the traveler along the bridge span, said traveler frame being of lesser length than 60 the width of the bridge, and an extension frame rollably mounted on the traveler in a manner to roll therealong and extend beyond either end of the traveler frame to a point so as to project 65 beyond the sides of the bridge and provided with a platform adapted to support workmen in accessible relation to the bridge and means affording accessibility of workmen to said platform from said traveler frame. 70

6. In a structure as specified in claim 2, said extension frame provided with a plurality of working platforms one above the other, and steps leading from one to the other. 75

7. In a structure as specified in claim 2, said 75

extension frame provided with a plurality of working platforms one above the other, and steps leading from one to the other and the sides of said extension frame enclosed in wire mesh walls, 5 while leaving the outer ends of the extension frame open.

8. Bridge span inspection apparatus comprising a traveler frame extending transversely of and under the bridge span, tracks carried by the bridge extending longitudinally thereof and rollers carried by the traveler engaging the tracks for rolling the traveler along the bridge span, said traveler frame being of lesser length than the width of the bridge, and an extension frame rollably mounted on the traveler in a manner to roll therealong and extend beyond either end of the traveler frame to a point adjacent the sides of the bridge and provided with a platform adapted to support workmen in accessible relation to the bridge, said extension frame provided with a downwardly extending portion arranged to come adjacent the bridge side trusses and to the bottom thereof when the frame is extended.

9. Bridge span inspection apparatus comprising a traveler frame extending transversely of and under the bridge span, tracks carried by the bridge extending longitudinally thereof and rollers carried by the traveler engaging the tracks for rolling the traveler along the bridge span, said traveler frame being of lesser length than the width of the bridge, and an extension frame rollably mounted on the traveler in a manner to roll therealong and extend beyond either end of the traveler frame to a point adjacent the sides of the bridge and provided with a platform adapted to support workmen in accessible relation to the bridge, said extension frame provided with a downwardly extending portion arranged to come adjacent the bridge side trusses and to the bottom thereof when the frame is extended, and provided with a portion extending outwardly under and beyond the bridge side trusses.

10. Bridge span inspection apparatus comprising a traveler frame extending transversely of and under the bridge span within its main side trusses, tracks carried by the bridge extending longitudinally thereof and rollers carried by the traveler frame engaging the tracks for rolling the traveler frame along the bridge span, and a

cross traveler frame rollably suspended below the traveler frame for rolling therealong, provided with a hanging tower portion at each end adapted respectively to extend beyond the ends of the traveler when rolled either way and come adjacent the inner sides of the bridge side trusses. 5

11. In the construction as specified in claim 10, a main floor or workman-supporting platform on said cross traveler frame and a plurality of superimposed workmen platforms on said hanging towers. 10

12. In the construction as specified in claim 10, an extension from the lower end of said hanging towers adapted to project outward under the bridge side truss when the tower is adjacent 15 thereto.

13. Bridge span inspection apparatus comprising a traveler frame extending transversely of and under the bridge span within its main side trusses, tracks carried by the bridge extending longitudinally thereof and rollers carried by the traveler frame engaging the tracks for rolling the traveler frame along the bridge span, and a cross traveler frame rollably suspended below the traveler frame for rolling therealong, provided with 20 a hanging tower portion at one end adapted to extend beyond the end of the traveler when rolled toward the side of the bridge and come adjacent the inner side of the bridge side truss. 25

14. In the construction as specified in claim 13, 30 an extension from the lower end of said hanging tower adapted to project outward under the bridge side truss when the tower is adjacent thereto.

15. Bridge span inspection apparatus comprising a traveler frame extending transversely of and under the bridge span within its main side trusses, tracks carried by the bridge extending longitudinally thereof and rollers carried by the traveler frame engaging the tracks for rolling 35 the traveler frame along the bridge span, and a hanging tower portion at each end of said traveler arranged and adapted to come adjacent the inner sides of the bridge side trusses, and platforms on said hanging tower portions adapted to 40 support workmen for working on the bridge and means affording accessibility of workmen to said platforms from said traveler frame. 45
